(57) CLAIM

The ornamental design for a “wake tower construction”, as shown and described.

DESCRIPTION

FIG. 1 is a generally perspective view of a wake tower construction showing my new design;

FIG. 2 is a right side view thereof, the opposite side being a mirror image of that shown;

FIG. 3 is a front view thereof;

FIG. 4 is a rear view thereof;

FIG. 5 is a top plan view thereof;

FIG. 6 is an enlarged cross-sectional view taken along lines 6—6 of FIG. 2; and,

FIG. 7 is an enlarged cross-sectional view taken along lines 7—7 of FIG. 2.

The broken line showing of environmental structure in FIGS. 1 and 2 is for illustrative purposes only and forms no part of the claimed design.
